(57) **CLAIM**

The ornamental design for a light up jump rope, as shown and described.

DESCRIPTION

FIG. 1 is a right front perspective view of an enlarged single handle of the light up jump rope showing my new design, shown separately for clarity of illustration;

FIG. 2 is a front elevation view of the enlarged single handle shown separately for clarity of illustration;

FIG. 3 is a rear elevation view of the enlarged single handle shown separately for clarity of illustration;

FIG. 4 is a right side elevation view of the enlarged single handle shown separately for clarity of illustration;

FIG. 5 is a left side elevation view of the enlarged single handle shown separately for clarity of illustration;

FIG. 6 is a top plan view of the enlarged single handle shown separately for clarity of illustration;

FIG. 7 is a bottom plan view of the enlarged single handle shown separately for clarity of illustration; and,

FIG. 8 is a reduced scale right front perspective view of the complete jump rope shown with the rope cut away to show no specific length.

The rope portion of the jump rope is shown broken away to indicate it has no specific length.

The broken lines illustrate portions of the light up jump rope which forms no part of the claimed design.
